WORK CLAMP

Frank B. Brown, Riverside, R. I.

Application January 23, 1936, Serial No. 60,540

3 Claims. (Cl. 29—67)

The present invention relates to new and useful improvements in miter boxes, particularly for metal work, although it will be understood that a device constructed in accordance with the present invention may be used for any other material and for any other purposes for which it may be found adapted and desirable.

One of the important objects of the invention is to provide, in a manner as hereinafter set forth, a device of the aforementioned character embodying novel means through the medium of which pieces of work of various shapes may be rigidly clamped in position to be operated on, the clamping means further permitting one or more pieces to be secured at a time.

Another very important object of the invention is to provide novel means for detachably and adjustably securing the device to a base.

Other objects of the invention are to provide a miter box of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a miter box constructed in accordance with the present invention, a portion of the socket and post being broken away in section.

Figure 2 is a view in front elevation of the miter, box, and clamp.

Figure 3 is a view in vertical transverse section through the rear end portion of the box, taken substantially on the line 3—3 of Figure 1, showing a piece of work in position.

Figure 4 is a view in vertical transverse section through the box, showing a substantially T-shaped bed mounted therein to accommodate flat work.

Figure 5 is a view in vertical transverse section through the box, showing a plurality of pieces of round work clamped therein.

Figure 6 is a detail view in perspective of the bed which is used when a plurality of pieces of round work are to be clamped in the box, as shown in Figure 5.

Figure 7 is a view in side elevation of a portion of the invention, showing the box swung to a vertical position.

Figure 8 is a view in front elevation of the invention, showing the device being used for soldering.

Figure 9 is a detail view in perspective of the detachable table which is attached to the miter when the device is used for soldering, as shown in Figure 8.

Referring now to the drawings in detail, it will be seen that the embodiment of the invention which has been illustrated comprises a base 10 which is rigidly and permanently secured to a bench or other suitable support 2 by bolts or the like 3. The base 10 includes a socket 4 for the reception of an adjustable and removable post 5 which is secured in position by a set screw 6.

In its upper end portion the post 5 has formed therein a vertical slot or groove 7 which is traversed by a pin 8. The slot 7 accommodates the depending shank 9 of a substantially Y-shaped miter which is designated generally by the reference numeral 10, said shank 9 being journaled on the pin 8. The rear end of the groove 7 is closed, as at 11, for supporting the miter 10 in a vertical position, as illustrated to advantage in Figure 1 of the drawing. The miter 10 includes oppositely inclined arms 12 terminating in vertical free end portions 13, said arms 12 and portions 13 having slots 14 therein for the reception of a saw (not shown).

Rigidly secured on the miter 10 and projecting at right-angles therefrom is a substantially V-shaped box 15 for the reception of the work 16, as best seen in Figures 3 and 5 of the drawings. In its rear end portion, the box 15 has formed in its bottom an opening 17 for the reception of a center punch or drill. The work is removably secured in the box 15 through the medium of a clamp which is designated generally by reference numeral 18. The clamp 18 comprises a metal bar bent to form a horizontal intermediate portion 19, oppositely inclined portions 20, and inturned end portions 21 constituting hooks engageable under the walls of the box 15. The portions 19 and 20 of the clamp 18 have threaded openings 22 therein which accommodate winged clamping screws 23. When a single piece of work is to be secured, as seen in Figure 3, but a single clamping screw 23 may be necessary, this being the one which is mounted in the portion 19. However, when a plurality of pieces of work are to be secured in position a number of clamping screws may be used, as shown in Figure 5 of the drawings.

When a plurality of round pieces of work are to be secured in the box 15, a metallic plate 24 of angular cross-section is mounted on the lowermost piece of work in the

bottom of the box 15 for the other pieces to rest on. When it is desired to secure flat work in the box 15, a substantially T-shaped bed 25 (see Figure 4) is mounted in said box. The bed 25, it will 5 be observed, may be made from two lengths of angle iron rigidly secured together.

The construction and arrangement is such that the miter 10, with the box 15 thereon, may be swung to the position shown in Figures 7 and 8 10 of the drawings, in which position said miter 10 rests on the bottom of the groove 7 in the post 5. When in this position, the device may be used for soldering by securing an electric soldering iron 26 in the box 15. Then, a table 27 is mounted on 15 the now horizontal miter 10. The table 27 includes a substantially V-shaped extension 28 which projects into the box 15 below the soldering iron 26. The table 27 further includes depending sides 29 having inwardly and upwardly turned 20 flanges 30 on their lower ends engageable with the portions 13 of the miter 10 for slidably and 25 removably mounting said table in position. In Figure 8 of the drawings, the reference numeral 31 designates a quantity of solder on the table 27. 30 It is thought that the operation of the device will be readily apparent from a consideration of the foregoing. With the box 15 in horizontal position, as shown in Figure 1 of the drawings, one or more pieces of work may be expeditiously 35 secured in position in the box 15 through the medium of the clamp 18, said pieces, of course, traversing the slots 14 in the miter 10 for engagement by the hack saw, as will be obvious. As hereinbefore stated, the mounting of the miter 35 10 permits the device to be readily adjusted. Further, the miter 10 with the box 15 may be conveniently removed when desired for any purpose.

It is believed that the many advantages of a 40 miter box constructed in accordance with the present invention will be readily understood, and although a preferred embodiment of the device is as illustrated and described, it is to be understood that changes in the details of construction 45 and in the combination and arrangement of parts may be resorted to which will fall within the scope of the invention as claimed.

What is claimed is:

1. A device of the class described comprising a 50 base including an upstanding socket, a post re-

movably and adjustably secured in said socket, means for securing the post in adjusted position, said post having a groove in its upper end portion, said groove being closed at one end, a substantially Y-shaped clamping member mounted on 5 the post and including a shank journaled in the groove, said shank being engageable with the end wall of the groove for supporting the clamping member in a vertical position and being further engageable with the bottom of said groove for 10 supporting said clamping member in a horizontal position, and a substantially V-shaped box rigidly mounted on the clamping member, said clamping member having slots therein for the reception of a saw.

2. A device of the class described comprising a 15 post, a member mounted for swinging movement in a vertical plane on said post, a substantially V-shaped box mounted on said member, a table 20 removably mounted on the member and including a substantially V-shaped end portion engageable in the box, and means for removably securing a 25 soldering iron in the box.

3. A device of the class described comprising a 30 base including an upstanding socket, a post 25 mounted in said socket, said post having a groove in its upper end portion, said groove being closed at one end, a member mounted for swinging movement in a vertical plane on the post, said member including a pair of oppositely inclined arms and 35 a shank journaled in the groove, said shank being engageable with the end wall of the groove for supporting the member in a vertical position and being further engageable with the bottom of the 40 groove for supporting said member in a horizontal position, parallel extensions on the free ends of the arms, a substantially V-shaped box rigidly secured on the arms of the member, a table, for supporting a quantity of solder, removably mounted on the member, said table including a 45 substantially V-shaped extension projecting into the box and further including depending sides, inwardly and upwardly turned flanges on the lower ends of the sides engageable with the parallel end portions of the arms for removably mounting the table in position on the member, and a clamp on the box for detachably securing a 50 soldering iron in said box.
